US00D981788S

(12) **United States Design Patent** (10) **Patent No.:** **US D981,788 S**
(45) **Date of Patent:** **** Mar. 28, 2023**

(54) **CUP**

(71) Applicant: **MiiR Holdings, LLC**, Seattle, WA (US)

(72) Inventors: **Bryan Pape**, Seattle, WA (US); **Joe Gray**, Seattle, WA (US)

(73) Assignee: **MiiR Holdings, LLC**, Seattle, WA (US)

(**) Term: **15 Years**

(21) Appl. No.: **29/814,206**

(22) Filed: **Nov. 4, 2021**

Related U.S. Application Data

(63) Continuation of application No. 29/740,319, filed on Jul. 2, 2020, now Pat. No. Des. 946,352.

(57) **CLAIM**

We claim the ornamental design for a cup, as shown and described.

DESCRIPTION

FIG. 1 is a top perspective view of a first embodiment of a cup showing our new design, shown with an environmental lid for clarity of disclosure;

FIG. 2 is another top perspective view of a first embodiment of a cup showing our new design, shown with no lid for clarity of disclosure;

FIG. 3 is a rear, elevation view thereof;

FIG. 4 is a front, elevation view thereof;

FIG. 5 is a left-side, elevation view thereof;

FIG. 6 is a right-side, elevation view thereof;

FIG. 7 is a top, plan view thereof;

FIG. 8 is a bottom, plan view thereof;

FIG. 9 is a top perspective view of a second embodiment of a cup showing our new design;

FIG. 10 is a rear, elevation view thereof;

FIG. 11 is a front, elevation view thereof;

FIG. 12 is a left-side, elevation view thereof;

FIG. 13 a right-side, elevation view thereof;

FIG. 14 is a top, plan view thereof; and,

FIG. 15 is a bottom, plan view thereof.

The broken line showing of a lid in FIG. 1 depicts environment and forms no part of the claimed design. Portions of the cup shown in broken line form no part of the claimed design.

1 Claim, 9 Drawing Sheets
